Primary Examiner — Zenia Bennett*(74) Attorney, Agent, or Firm* — Workman Nydegger(57) **CLAIM**

The ornamental design for a sports board, as shown and described.

DESCRIPTION

FIG. 1 is a top plan view of a sports board of the present invention showing the design;

FIG. 2 is a bottom plan view of the sports board of FIG. 1; FIG. 3 is a front elevational view of the sports board of FIG. 1;

FIG. 4 is a rear elevational view of the sports board of FIG. 1; FIG. 5 is a right side elevational view of the sports board of FIG. 1;

FIG. 6 is a left side elevational view of the sports board of FIG. 1;

FIG. 7 is a perspective view from front and above of the sports board of FIG. 1;

FIG. 8 is a perspective view from front and below of the sports board of FIG. 1; and,

FIG. 9 is a perspective view from front and above, with a tow rope thereof shown in broken, phantom lines.

The broken, phantom lines shown in the drawings illustrate portions of the sports board that form no part of the claimed design.
